LOWER PUMP VALVE ASSEMBLY

Filed Jan. 19, 1927

INVENTOR.

DANIEL E. BYERS

BY.

H. A. Dickman
ATTORNEY

UNITED STATES PATENT OFFICE.

DANIEL E. BYERS, OF LONG BEACH, CALIFORNIA.

LOWER-PUMP-VALVE ASSEMBLY.

Application filed January 19, 1927. Serial No. 162,159.

This invention relates to lower valves for deep well pumps which pumps are either of the type in which the barrel reciprocates and the plunger is stationary or those in which the plunger reciprocates and the barrel is stationary. In the latter case if there is a high gas pressure which tends to raise the lower valve off its mounting, my construction is particularly applicable, for the valve is held positively in its seat.

An object of my invention is to provide a lower pump valve assembly which is positively held in its mounting during the operation of the pump.

Another object is to provide means whereby the locking arrangement may be longitudinally adjusted so as to positively seat the assembly in its mounting.

A further object is to provide a valve assembly of the character stated in which the locking members may be hardened, thus materially increasing the useful life of the device.

Still another object is to provide a removable locking means which may be readily replaced when worn.

Other objects, advantages, and features of invention may appear from the accompanying drawing, the subjoined detailed description, or in the appended claims.

In the drawing—

Fig. 1 is a longitudinal sectional view of my lower pump valve assembly in operative position in a pump.

Fig. 2 is a longitudinal sectional view of my locking shoe.

Fig. 3 is a plan view of the lower valve cage.

Referring more particularly to the drawing:

A mounting block 1 is secured to the lower end of the tubing 2 in which the pump 3 is mounted. The block 1 is provided with a seat 4 at the upper end thereof, the purpose of which will be further described.

The tubular locking shoe 5 comprises an upper section 6 and a lower spring dog section 7. The upper section 6 is formed with a conical ring 8 adjacent the upper end thereof, which ring is adapted to rest on the seat 4 and thus prevent the liquid from passing downwardly through the mounting block 1. A threaded section 9 is formed on the upper end of the locking shoe 5 which is adapted to receive the cage 10. The cage 10 is thread-

ed on the section 9 and holds the usual valve seat 11 upon which the ball 12 is adapted to rest. A transverse bridge 13 is integrally formed adjacent the upper end of the cage 10 and a plurality of holes 14 extend therethrough to permit the passage of liquid.

A bumper pin 15 projects downwardly from the bridge 13 and is integrally formed therewith, the purpose of said pin being to limit the upward movement of the ball 12. Also this pin prevents the ball from lying over the holes 14 to obstruct the free passage of the liquid through the holes. The upper end of the cage 10 may be either internally or externally threaded as desired to receive the piston section 16 or the pump barrel, depending upon which type of pump the assembly is used with.

The lower spring dog section 7 is formed of a hardened material and is threaded onto the lower end of the upper section 6, as shown at 17. A plurality of longitudinally-extending slots 18 are formed in the section 7 to permit the collapse of the lower end thereof when the assembly is withdrawn from the well. A sleeve 19 screws into the lower end of the block 1 and is provided with a ring seat 20 which seat is hardened to resist wear.

An annular groove 21 is formed adjacent the lower end of the dog section 7 which groove is adapted to fit into the hardened seat 20. The outward tension of the dog 7 serves to securely hold the assembly in position in the block. The seat 20 and dog section 7 are both hardened and will therefore resist wear for a greater length of time. If the dog 7 should break or otherwise fail it is a simple matter to unscrew it from the upper section 6 and replace with a new one.

From time to time as the seat 4 is reground or refaced, the locking shoe 5 will extend lower in the block 1 and consequently the sleeve 19 would not hold the shoe tightly in position. To remedy this, I provide a lock nut 22 which screws onto the sleeve 19 and bears against the bottom of the block 1 whereby the said sleeve may be adjusted to the required position so that the ring 8 is held tightly in the seat 4.

Having described my invention, I claim:

1. In a pump adapted to be mounted in tubing, a block on the lower end of said tubing, a locking shoe mounted in said block, said shoe comprising an upper section seated in said block, a lower dog section, a sleeve

secured to the lower end of said block, said sleeve being adapted and arranged to receive said locking dogs, and means to adjust said sleeve whereby the locking shoe is tightly held in the block.

2. In a pump adapted to be mounted in tubing, a block on the lower end of said tubing, a locking shoe mounted in said block, said shoe comprising an upper section seated 10 in said block, a lower dog section, a sleeve threaded into the lower end of said block, and a lock nut threaded onto said sleeve against said block whereby the sleeve may be adjusted to hold said locking shoe in seated position 15 in the block.

3. In a pump adapted to be mounted in tubing, a block secured to the lower end of said tubing, a seat adjacent the upper end of said block, a hollow locking shoe, a ring on 20 said shoe adapted to seat on said block seat, locking dog section on the lower end of said locking shoe, said dog section being threaded to the upper section, and adjustable means adapted to engage said dogs to hold the locking shoe in seated position.

4. In a pump adapted to be mounted in tubing, a block secured to the lower end of said tubing, a seat adjacent the upper end of said block, a hollow locking shoe, a ring on 30 said shoe adapted to seat on said block seat, locking dog section on the lower end of said locking shoe, said dog section being threaded to the upper section, adjustable means adapted to engage said dogs to hold the locking shoe

in seated position, said means comprising 35 sleeve threaded into said block, and a lock nut threaded onto the sleeve against said block.

5. In a pump adapted to be mounted in tubing, a block on the lower end of said tubing, a locking shoe mounted in said block, 40 said shoe comprising an upper section seated in said block, a lower dog section, means on said block adapted to receive said dogs, a valve cage secured to the upper end of said locking shoe, said valve cage comprising an 45 integral bridge having a plurality of holes extending therethrough, and an integral bumper pin depending from said bridge.

6. In a pump adapted to be mounted in tubing, a block secured to the lower end of 50 said tubing, a seat adjacent the upper end of said block, a locking shoe comprising an upper seating section, a ring on said upper section adapted to rest on the lock seat, threads on the upper end of said upper section, a 55 valve cage screwed onto said threads, a lower locking dog section threaded onto the lower end of the upper section, a sleeve threaded into the lower end of the block, a lock nut threaded onto the sleeve and adapted to bear 60 against the block, said sleeve having a ring seat therein, and said locking dogs having a groove formed therein to receive the seat whereby the locking shoe is securely held in seated position.

In testimony whereof, I affix my signature.

DANIEL E. BYERS.
